(57) CLAIM

The ornamental design for pedals with floor lock, as shown
and described.

DESCRIPTION

FIG. 1 is a perspective view of pedals with floor lock
showing our new design;

FIG. 2 is another perspective view thereof;

FIG. 3 is a right side elevational view thereof;

FIG. 4 is a left side elevational view thereof; and,

FIG. 5 is a bottom plan view thereof.

The broken lines shown in FIGS. 1 and 2 drawing views are
for illustrative purposes only and form no part of the claimed
design.
